DESIGN FOR A CIGARETTE LIGHTER OR THE LIKE

Irving Florman, New York, N. Y.

Application July 16, 1945, Serial No. 120,721

Term of patent 14 years

(Cl. D48—27)

To all whom it may concern:

Be it known that I, Irving Florman, a citizen of the United States, residing at New York, in the county of New York and State of New York, have invented a new, original, and ornamental Design for Cigarette Lighter or the like, of which the following is a specification, reference being made to the accompanying drawing, forming a part thereof.

Figure 1 is a view in perspective of a cigarette lighter or the like showing my new design; the lighter being in closed position;

I claim:

The ornamental design for a cigarette lighter or the like, substantially as shown.

IRVING FLORMAN.
